UNITED STATES PATENT OFFICE.

ERNEST CANTELO WHITE, OF NEW YORK, N. Y., ASSIGNOR TO DUPLEXALITE CORPORATION, OF NEW YORK, N. Y., A CORPORATION OF NEW YORK.

LIGHTING-FIXTURE.

1,396,486.

Specification of Letters Patent. Patented Nov. 8, 1921.

Application filed April 11, 1919. Serial No. 289,184.

To all whom it may concern:

Be it known that I, ERNEST CANTELO WHITE, a citizen of the United States, residing in the borough of Manhattan of the city of New York, in the State of New York, have invented certain new and useful Improvements in Lighting-Fixtures, of which the following is a specification, reference being had to the accompanying drawing, forming a part hereof.

The object of my invention is to produce a lighting fixture in which direct illumination is combined with indirect illumination in a novel and useful way by the employment of the outer and inner surface of a reflector, the outer surface of such reflector being illuminated by light transmitted by a lower diffusing member.

The figure is an elevation of an appliance embodying the invention, in which 1 is a light source, of any desired type or construction; the reflector 2 has a lower contracted portion and an upper flaring rim, the curvature of the sides being generally of the type shown, the outer curve being concave in vertical elevation to receive light rays as hereinafter explained; 3 is a lower member of translucent glass which is attached to the upper reflector by any method desired, in this instance by means of screws 4. The upper reflector 2 is here shown attached to a ceiling fixture by means of chains 6 fastened to the side of the reflector by means of screws 7. This method of fastening the various parts is not essential but may be varied at will, as the method of attachment is not a feature of this invention. The operation of the invention and its novelty is as follows: The reflector 2 is reflective of light either by reason of its texture or because of reflecting coatings or appliances on its inner surface 8 as well as on its outer surface 9. The light rays are sent in three useful directions. Light ray r , typical of the first direction is shown incident from the light source, to the inner surface 8 of reflector and reflected in direction r' to the ceiling. A substantial part of the light is thus sent to the ceiling or upper parts of the room and reflected thereby below to all portions of the surface to be illuminated.

The balance of the light rays emitted by the source are sent through the open mouth 5 of the reflector and strike the inner surface of the translucent member 3, and create

a secondary luminous source. The rays s which strike such inner surface at 10, are transmitted and diffused as at s' and sent in directions shown. Other rays t , which strike the member 3 as at 11, will be reflected within the member in direction t' for transmission and diffusion through the wall of the member in direction t'' causing such transmitted rays to strike the reflector 9, causing it to become luminous and creating a third source of light. The relative luminous intensity of the various parts depends on the proportion of reflector to the lower member, in this instance a bowl, and takes into account the curvature of the reflector as well as the size, shape, material and point of attachment of the bowl to the reflector. In any event the member 3 will have to be of sufficient size to extend beyond the mouth of the reflector yet within diameter of the upper rim of the reflector so that such reflector can be seen from below as an illuminated body, and it is contemplated to have the reflector house the light source and be the major part of the device. The rays which pass through the member 3 will be scattered in the manner shown and some out of the bundle of rays thus scattered will follow the directions shown.

The flaring reflector ring is a necessity to secure even outer and inner illumination and the novelty consists in utilizing light rays from the lower member 3, causing it to act as a secondary light source for the purpose of illuminating the exterior of the reflector. The reflector is opaque or practically so, and preferably is of metal with reflecting plates or coating on its outer and inner surface. The lower member 3 is shown of translucent glass which may be plain or ornamented and is preferably of even texture and color so as to become illuminated and adapted to act as a secondary light source for the purpose specified.

In the claims I have used the term member in describing the lower transmitting secondary source, as the shape is immaterial as it may be flattened, curved, or spherical in outline as long as it is of an inclosing shape and texture to permit the illumination of the reflector 2 by rays transmitted through the walls of the member.

Having described my invention what I claim is:

1. A lighting fixture comprising, a light

source, a fixture support, an opaque reflector surrounding the source, such reflector being open at the top and bottom to permit the passage of light rays through such openings, and having an upwardly flaring concave outer surface in vertical cross-section and having attached to the lower opening of the reflector a translucent member extending beyond the lower opening and within the diameter of the upper opening, constructed to direct a portion of the light rays transmitted thereby to the outer surface of the reflector.

2. A lighting fixture comprising a light source, a fixture support, a reflector open at

the top and bottom for the passage of light rays through such openings, such reflector having an upwardly flaring concave outer surface in vertical cross-section and both inner and outer surfaces reflective of light, 20 and having a lower translucent member extending beyond the lower opening of the reflector and within the diameter of the upper opening thereof, constructed to direct a portion of the light rays transmitted there- 25 by to the outer surface of the reflector.

This specification signed this 7th day of April, A. D. 1919.

ERNEST CANTELO WHITE.
